Arthur Crane Jr.
WITNESS:

UNITED STATES PATENT OFFICE

OTTO DEPPMEYER, OF UTICA, NEW YORK

POCKET KNIFE

Application filed December 26, 1930. Serial No. 504,879.

This invention relates to improvements in pocket knives and has for the primary object, the provision of a novel handle which will materially reduce the cost of manufacture of the device over similar devices and which will be durable and efficient.

Another object of this invention is the provision of a handle formed from a single length of woven wire providing the handle with side shield portions for the blade when in a closed position and an efficient grip for the user when the blade is extended or in an operative position.

A further object of this invention is the twisting of the wire intermediate the ends of the handle that finger notches are provided whereby the blade may be easily gripped for swinging the latter into active or operative position and further forms a stop for the inward movement of the blade relative to the handle and also aids in permitting a person to obtain a firm grip on the handle.

With these and other objects in view as will become more apparent as the description proceeds, the invention consists in certain novel features of construction, combination and arrangement of parts, as will be hereinafter more fully described and claimed.

For a complete understanding of my invention, reference is to be had to the following description and accompanying drawings, in which—

Figure 1 is a side elevation illustrating a pocket knife constructed in accordance with my invention.

Figure 2 is an edge elevation illustrating the same.

Figure 3 is a similar view to Figure 2 showing the opposite edge of the knife.

Figure 4 is a side elevation with the blade collapsed or folded into the handle.

Figure 5 is a sectional view taken on the line 5—5 of Figure 1.

Referring in detail to the drawings, the numeral 1 indicates a knife blade of a conventional type having the usual rounded or cam shaped end 2 provided with a shoulder 3 adjacent thereto for engagement with the end of the handle when the blade is in an active

or operative position. The foregoing description relates to a well known construction of blade to which my invention is applied. The handle 4 is constructed from a single length of heavy gage wire bent intermediate its ends to form parallel portions 5 and which provide the back to the handle. The parallel portions 5 intermediate their ends are bent to form offsets 6 and are slightly bowed or spaced as shown at 7 to form a stop for limiting the movement of the blade 1 into the handle 4. The wire after forming the back portion 5 is bent angularly to provide an end portion 8 and then bent parallel and in spaced relation to the portions 5 in forming sides or shields 9 for the blade 1 when in a collapsed or folded position. The wire after forming the sides 9 is bent in overlapping relation and extended through the offset portions 6. The ends of the wire after forming the side portions 9 and when extended through the offsets 6 of the portion 5 are crossed and then bent to provide spaced arms 10 extending substantially parallel with the portions 5 or the back of the handle 4 and have the blade 1 pivoted thereto.

The arms 10 also complete the sides or shields for the knife blade. The end 11 of the portion 5 rides upon the curved end 2 of the blade and when the latter is in extended position engages the shoulder 3 to limit the movement of the blade beyond an extended or active position or to prevent collapsing of the blade when in the act of cutting. It will be noted that the wire when bent to extend through the offsets 6 provides finger notches 12 for the sides of the handle whereby the blade may be easily gripped when desiring to swing the latter upwardly of the handle. The portions of the wire forming the sides of the handle are slightly spaced to permit the blade to move freely into and out of the handle.

A handle constructed in accordance with the foregoing may be manufactured at a very low cost and will form a very efficient handle capable of withstanding abuse and hard usage and will form a blade shield for the blade when the latter is in an inactive or inoperative position. The handle further

permits a person to easily obtain a firm grip thereon when using the blade for cutting purposes.

While I have shown and described the preferred form of my invention, it will be understood that minor changes in construction, combination and arrangement of parts may be made without departing from the spirit and scope as claimed.

Having thus described my invention, what I claim is:

1. A knife comprising a handle constructed from a single length of material bent intermediate its ends to provide parallel portions defining the back of the handle, the material after forming the parallel portions extending angularly thereto to provide an end portion and then bent parallel and in spaced relation to the back of the handle to provide 15 a blade shield, the ends of the material extending from the shield providing arms, and a blade pivoted to the arms and receivable by the shield, the material of the parallel portions of the back bent to form offsets and 20 bowed to provide a stop for limiting the movement of the blade into the shield.

2. A knife comprising a handle constructed from a single length of material bent intermediate its ends to provide parallel portions 25 defining the back of the handle, the material after forming the parallel portions extending angularly thereto to provide an end portion and then bent parallel and in spaced relation to the back of the handle to provide 30 a blade shield, the ends of the material extending from the shield providing arms, and a blade pivoted to the arms and receivable by the shield, the material of the parallel portions of the back bent to form offsets and 35 bowed to provide a stop for limiting the movement of the blade into the shield, the material of the shield and arms bent about 40 the offsets to provide finger spaces for permitting the blade to be gripped for moving 45 the latter outwardly of the shield.

In testimony whereof I affix my signature.

OTTO DEPPMEYER.
